UNITED STATES PATENT OFFICE.

WILLIAM E. FOWLER, JR., OF MOUNT LEBANON, PENNSYLVANIA, ASSIGNOR TO
DAVIS BRAKE BEAM COMPANY, OF JOHNSTOWN, PENNSYLVANIA, A CORPORA-
TION OF PENNSYLVANIA.

SECURING BRAKE-BEAM SUPPORTS TO SPRING PLANKS.

Application filed July 8, 1924. Serial No. 724,803.

To all whom it may concern:

Be it known that I, WILLIAM E. FOWLER, Jr., residing at Mount Lebanon, in the county of Allegheny and State of Pennsylvania, a citizen of the United States, have invented or discovered certain new and useful Improvements in Securing Brake-Beam Supports to Spring Planks, of which improvements the following is a specification.

In an application filed May 15, 1924, Serial Number 713,561, is shown and described means for so securing a brake beam supporting rail to the spring plank of a car truck that the rail will have a resilient bearing at two points on the underside of the plank, and a resilient bearing on the upper face of the plank, the latter point of bearing being intermediate the other two points. In the construction shown in said application, a loop is so formed in the rail approximately midway of its length as to be capable of being passed through an opening in the plank. At points on opposite sides of the loop, the rail bears directly on the underside of the plank and the portions of the rail between the loop and the points of bearing curve downward out of contact, and the loop is made of such a length relative to these curved portions that the loop cannot be passed through an opening in the spring plank sufficiently far to permit of a supporting pin to be passed through the loop without flexing and placing under tension the downwardly curved portions intermediate the loop and the points where the rail bears on the underside of the plank.

The invention described herein relates to a modification of the construction above described.

In the accompanying drawings forming a part of this specification Fig. 1 is a plan view showing a portion of a spring plank and a rail for supporting the brake beam secured to the spring plank as hereinafter described and claimed; Figs. 2 and 3 are sectional views on planes indicated respectively by the lines II-II and III-III, Fig. 1.

In the practice of the invention the supporting rail extends across the spring plank

1 and projects sufficient distances on each side thereof as to underlie the tension members 2 of the brake beam. When in operative positions, the tension members 2 rest in 55 seats 5 in shoes 4 which are movably mounted on the rails. In order to facilitate the movements of the brake beams away from the wheels, the outer portions of the rails are inclined as indicated at 3. Suitable 60 stops 3^a are provided to prevent accidental movement of the shoes from the rails.

As shown, the supporting rail is arranged under the spring plank and the intermediate portion of the rail is so bent that the rail 65 will bear on the underside of the plank only at points adjacent to the edges of the plank as indicated at 6. The means employed for suspending the rail from the plank at a point intermediate the bearing points or 70 seats 6 are so constructed that the portions intermediate the seats are flexed and placed under tension before the rail can be connected to the plank. In the construction shown herein the suspending means consists 75 of a link 12 through which the rail is passed and a key or pin 10 adapted to be passed through the upper portion of the link when the latter has been passed through an opening 9 in the web of the spring 80 plank. As will be seen in Fig. 2, the portion 8 intermediate the bearings or seats 6, is separated a substantial distance from the underside of the plank and the link is made of such a length that it cannot pass 85 through the opening in the plank sufficiently far to permit of the insertion of the key or pin without deflecting the portion 8 from normal position. As the rail is made of resilient material, the flexure of the portion 8 90 will cause the seats together with the link 12 to bear resiliently on the plank and the pin 10 respectively.

While any suitable means may be employed to prevent material longitudinal 95 movement of the rail, it is preferred to so offset a portion of the rail as to form a recess or seat 7 for the reception of the ring or link. A desirable means for preventing a movement of the pin or key as will permit 100 of the dropping of the link, consists in forming a projection 13 on the underside of

the key adapted when the latter is in operative position to project into the opening 9 in the spring plank.

I claim herein as my invention:

- 5 1. The combination of a spring plank of a car truck having an opening therethrough, a supporting rail, a link surrounding the rail and extending through the opening in the plank and means passing through the portion of the link projecting above the plank and bearing on the upper side of the plank for supporting the link.
- 10 2. The combination of a spring plank of a car truck having an opening therethrough, a supporting rail having spaced points of bearing on the underside of the plank, a link surrounding the rail at a point intermediate the points of bearing on the plank and projecting through the opening in the

plank and means passing through the portion of the link projecting through the opening and bearing on the plank for supporting the link. 20

3. The combination of a spring plank of a car truck having an opening therethrough, a supporting rail having spaced points of bearing on the undersides of the plank and having a seat or offset intermediate such spaced bearing points, a link surrounding the rail and engaging the seat or offset therein and projecting through the opening in the plank, and means passing through the portion of the link above the plank and bearing on the plank for supporting the link. 25 30

In testimony whereof, I have hereunto set my hand. 35

WILLIAM E. FOWLER, JR.
